CONCRETE HANDLING APPARATUS

Filed April 14, 1947

UNITED STATES PATENT OFFICE

2,523,506

CONCRETE HANDLING APPARATUS

Ira J. Kuert, San Gabriel, Calif.; Bertha T. Kuert
executrix of said Ira J. Kuert, deceased

Application April 14, 1947, Serial No. 741,370

2 Claims. (Cl. 193—17)

1

This invention relates to a concrete handling apparatus.

The general object of the invention is to provide an improved, two-part pouring chute for use with a concrete handling apparatus.

Other objects and advantages of the invention will be apparent from the following description taken in connection with the accompanying drawings, wherein:

Fig. 1 is a fragmentary side elevation with parts in section, showing the improved pouring spout and associated parts;

Fig. 2 and Fig. 3 are views similar to Fig. 1, showing the parts in other positions.

Referring to the drawing by reference characters, I have shown my improved chute as mounted on a tower 22 which consists of pipes 22' which are connected by coupling members 23. The tower includes transverse members 54 connected to the pipes 22'. The tower supports a hollow, rotary drum 92 which may be associated with a concrete mixer, and the drum forms no part of the present invention.

In the drawings my improved pouring chute is indicated generally at 100 and includes a concrete receiving portion 101 which has a bracket 102 secured thereon. The bracket 102 is mounted on a shaft 103 which is secured to the mixer frame 103'. The chute further includes a discharge portion 104 which has a bracket 105 fixed thereon. The bracket 105 is mounted on a shaft 106 on the receiving portion 101 of the chute and as a result the discharge portion of the chute is free to pivot on the receiving portion of the chute and the latter is free to move about the shaft 103. Thus the chute portion 101 may be moved from a position shown in Fig. 1 where it is disposed to receive concrete from the mixer, to a position shown in Fig. 2, where the portion 101 is out of the path of the concrete so that discharge of concrete ceases and then to the position of Fig. 3, where the portion 104 is out of the path of the bucket 49.

In order to shift the two parts of the chute as a unit, I provide a bell crank 110 which has a handle 111 thereon. The bell crank is mounted on a shaft 112 which is arranged on a portion 113 on the mixer. The end of the bell crank opposite the handle 111 has a pivot 114 thereon which pivotally engages one end of a curved link 115. The other end of the link 115 is pivotally connected at 116 to a bracket 117 on the bracket 102. The arrangement is such that when the handle 111 is swung clockwise in Fig. 1, the chute

2

as a unit will be moved from the position of Fig. 1 to the position shown in Fig. 2.

A spring 118, fixed at one end to a shaft 119 on the mixer, has the other end secured at 120 to the link 115 and when the parts are in the position shown in Fig. 1, the pivot 114 is over the center line connecting the pivots 112 and 116 and thus the spring 118 holds the parts in the position shown in Fig. 1.

10 To move the discharge portion 104 of the chute, I mount a bell crank 125 on the shaft 119. The bell crank includes a handle 126 at one end and at the other end is pivotally connected at 127 to curved links 128, which, in turn, is connected at 129 to the bracket 105 on the portion 104.

It will thus be seen that by operating the handle 111 the entire chute as a unit may be moved from the position shown in Fig. 1 to the position shown in Fig. 2 and that thereafter by operating 20 the handle 126 the discharge portion of the chute may be moved to the position shown in Fig. 3. Thus it will be seen that the chute first moves out of concrete receiving position and that thereafter the discharge portion of the chute moves 25 out of the path of the bucket.

In order to hold the portion 104 in the position of Fig. 3, I provide a counterbalancing spring 130 which is secured at 131 to a link 132 fastened to the shaft 119 at the end opposite the bell crank 125; the other end of this spring 130 is fastened to the supporting frame about the mixer 90.

From the foregoing description it will be apparent that I have invented an improved concrete handling apparatus which is highly efficient for its intended purpose.

Having thus described my invention, I claim:

1. A pouring chute for a concrete mixer, said chute consisting of two portions, namely a concrete receiving portion and a concrete discharge portion, said concrete receiving portion having a bracket thereon, a shaft supporting said bracket, said shaft being adapted to be secured to a concrete mixer frame, said discharge portion being normally aligned with the receiving portion, said discharge portion having a second bracket thereon, a second shaft supporting said second bracket, means to support the last mentioned shaft on the receiving portion, means to shift the two parts of the chute as a unit, said shifting means including a bell crank having a handle thereon, a shaft supporting said bell crank, means to mount the bell crank shaft on a mixer, the bell crank on the end thereof opposite the handle having a pivot thereon, a curved link,

a pivot connecting to the last mentioned end of the bell crank and the curved link, a bracket on which the other end of the curved link is pivotally connected, means to pivotally support the last mentioned bracket on the first mentioned bracket, and over-center means to hold the receiving portion and the discharge portions after they have been moved.

2. A pouring chute for a concrete mixer, said chute consisting of two portions, namely a concrete receiving portion and a concrete discharge portion, said concrete receiving portion having a bracket thereon, a shaft supporting said bracket, said shaft being adapted to be secured to a concrete mixer frame, said discharge portion being normally aligned with the receiving portion, said discharge portion having a second bracket thereon, a second shaft supporting said second bracket, means to support the last mentioned shaft on the receiving portion, means to shift the two parts of the chute as a unit, said shifting means including a bell crank having a handle thereon, a shaft supporting said bell crank, means to mount the bell crank shaft on a mixer, the bell crank on the end thereof opposite the handle having a pivot thereon, a curved link, a pivot connecting to the last mentioned end of the bell crank and the curved link, a bracket on which the other end of the curved link is pivotally connected, means to pivotally support the last mentioned bracket on the first mentioned bracket, a tension spring, means to secure one end of the spring to the link, a spring supporting shaft on the mixer, means to secure the other end of the spring to the spring supporting shaft, the relation of the last men-

tioned shaft and the point at which the spring is secured to the link being such that such connecting pivot is over the center line connecting the axis of the bell crank shaft and the axis of the pivotal support means of the last mentioned bracket on the first mentioned bracket, means to move the discharge portion of the chute relative to the receiving portion of the chute, said last mentioned means comprising a second bell crank on the spring supporting shaft, the second bell crank including a handle at one end, at the other end being pivotally connected to a second curved link, the other end of the second bell crank being connected to the second bracket.

IRA J. KUERT.
